UNITED STATES PATENT OFFICE.

JOHN PATTEN, OF BALTIMORE, MARYLAND.

METHOD OF HARDENING AND TEMPERING.

1,112,087.

Specification of Letters Patent. Patented Sept. 29, 1914.

Application filed August 15, 1912. Serial No. 715,283.

To all whom it may concern:

Be it known that I, JOHN PATTEN, a citizen of the United States, residing at Baltimore city, Maryland, have invented certain new and useful Improvements in Methods of Hardening and Tempering, of which the following is a specification.

My present invention relates to a method and apparatus for hardening the surface of 10 bodies of steel or other metal which may be hardened by heating and rapidly cooling.

The invention is applicable to the hardening of either plain or cylindrical surfaces or 15 the edges of cutting tools such as the various kinds of shears.

It is particularly adapted for hardening the interior surfaces of guns or engine cylinders although it may be applied generally to metal surfaces, and particularly to surfaces of thick metal bodies which will 20 quickly absorb the heat and which therefore do not require artificial cooling. Thus it is well adapted for hardening the surfaces of heavy guns, railroad rails and other articles having considerable mass.

In the preferred form of the invention I arrange an electric arc to impinge upon the surface to be hardened and then move the surface and the arc relatively until the arc 30 has traveled over the entire surface to be treated. While by this method a single restricted spot of the metal is treated at a time the relative movement of the arc and surface may be rapid and I can treat and 35 harden large surfaces very rapidly. I may use two electrodes adjacent the surface to be treated and pass an electric current through them, directing the arc against the surface by a magnet or other suitable means, or I 40 may include the metal body to be treated in the circuit and as one of the electrodes.

The particular electrical apparatus involved may be greatly varied and any suitable means may be used for supplying the 45 necessary electric current, regulating the same and regulating the feed of the carbon electrodes used in creating the arc as they are consumed.

In hardening dies and other metallic articles it has been heretofore customary to heat the whole of the die to the required temperature and then apply the cooling agent. The effect of this is to cause minute cracks to occur in the surface of the metal and also to 55 distort or warp the shape of the object. By employing my method, however, these dis-

advantages of the prior methods of hardening and tempering are eliminated owing to the fact that only a small spot is heated at a time and the heat only penetrates to a slight depth. The expansion of the spot which is heated is taken up by the compression of the surrounding metal so that the article as a whole is not distorted, and cracks are avoided. In carrying out my invention I may also employ a cooling agent to cool the heated spot immediately after the arc has heated the same. For the purpose of thus cooling the surface I use a suitable pipe which delivers the cooling agent to the surface immediately following the passage of the arc and the cooling agent may be water, or any other suitable liquid or gas. It is frequently desirable to use inert gas for this purpose as the contact of air with the heated surface would have a tendency to oxidize a part of the metal, and I avoid this oxidation by projecting a jet of the inert gas against the heated surface so that the air is driven away. Carbon dioxide or preferably the gases of combustion from an ordinary steam boiler furnace may be employed, although, of course, I do not wish to be limited to the use of these particular gases.

For the purpose of illustrating the use of my improved method of hardening and tempering I have shown several forms of apparatus adapted to harden and temper objects of various shapes, but it will be understood that the method herein claimed is not limited to these forms of apparatus as it will be obvious that various other forms may be devised.

In the drawings, Figure 1 is a longitudinal section showing an apparatus suitable for hardening the interior of the gun or long tubular body. Fig. 2 is a section on the line 2-2 of Fig. 3. Fig. 3 is a transverse section on the line 3-3 of Fig. 1. Fig. 4 is an end elevation of certain of the parts shown in Fig. 1. Fig. 5 is a longitudinal section through an apparatus for hardening and tempering comparatively short tubular bodies, such as engine cylinders. Fig. 6 is a fragmentary end elevation of certain parts shown in Fig. 5. Fig. 7 is an elevation with certain parts shown in section of an apparatus for tempering and hardening the exterior of cylindrical bodies. Fig. 8 is a section on the line 8-8 of Fig. 7. Fig. 9 illustrates a modified form of elec-

trodes which may be used in place of those shown in the other views. Fig. 10 is a perspective view of an apparatus for hardening and tempering a flat surface.

5 Referring to Fig. 1, 15 indicates the gun or tube to be hardened. A support or rest for the tube 15 is shown at 16 and has connected therewith a conductor 17. Fitting within the tube and adapted to be moved 10 longitudinally thereof is a head 18 which is secured on the end of a feed tube or rod 19 in any suitable manner as by means of the set screw 20. The outer end of the feed tube 19 is secured to a carriage 21 in any preferred manner as by means of a set screw 22, 15 and this carriage may be moved to feed the tube back and forth by any suitable mechanism such as that employed to move the carriage of the ordinary lathe. The head 18 is provided with an opening 23 through which 20 projects an electrode 24, preferably of carbon, this electrode being secured in a holder 25 in any suitable manner. The holder 25 is slidably arranged in a suitable casing 26 which is supported on and insulated from 25 the feed tube 19, a suitable insulator 27 being provided for this purpose. A rack 28 is secured to the holder 25 and a pinion 29 arranged in a suitable recess in the casing 30 26 has its teeth in engagement with the rack 28 and is secured to the end of a shaft 30 which extends longitudinally through the feed tube 19 and has its outer end supported in a bearing 31 which is insulated from the 35 tube 19 by means of a suitable insulator 32. A bell crank 33 is secured to the outer end of the shaft 30 and one arm of this bell crank is provided with a handle 34 and the other arm is operatively connected with a plunger 40 35 which is adapted to be reciprocated by a feeding mechanism 36 of any suitable construction. The feeding mechanism 36 may be of any of the constructions commonly employed for feeding the carbons in arc 45 lamps and as the detailed construction of this mechanism forms no part of the present invention it has been deemed unnecessary to illustrate and describe the same. At 37 I have indicated a source of electricity and 50 one terminal of this source has connected therewith the conductor 17 and the other terminal is connected with a rheostat 38. The rheostat 38 is connected with the feeding mechanism 36 by a conductor 39, an 55 ammeter 40 being provided for the purpose of indicating the current.

From the above it will be seen that the current from the source of electricity 37 will pass through the rheostat 38, the feeding 60 mechanism 36, the plunger 35, the bell crank 33 and shaft 30 to the holder 25 of the electrode 24. One end of the electrode 24 is spaced a slight distance from the inner surface of the tube 15 so that an arc will be 65 formed at this point, the current passing

from the electrode through the metal of the tube to the conductor 17 and thus returning to the source 37. For the purpose of cooling the surface immediately after the same has been heated by the arc I have provided 70 a tube 41 which is carried by the tube 19 and is provided with a nozzle 42 arranged to project a jet of the cooling medium onto the surface immediately after the passage of the arc thereover. It will thus be seen that 75 the jet of cooling medium will drive the air away from the heated spot and if an inert gas is used as the cooling medium oxidation of the cooling metal will be prevented.

In the operation of the mechanism the 80 tube 15 is rotated and the head 18 is gradually fed through the tube so that the arc covers the surface which it is desired to harden and temper, the path of the arc relative to the tube being of helical form.

85 The feeding mechanism 36 is preferably of the type which is adapted to maintain constant current through the circuit by varying the distance of the end of the electrode 24 from the surface over which it is being 90 passed. As will be readily understood this is accomplished by rocking the bell crank 33 and the shaft 30, thereby turning the gear 29 and moving the rack 28 and the holder 25. By providing the handle 33 the current 95 through the circuit may also be varied by the operator independently of the mechanism 36.

Referring to Figs. 5 and 6 it will be seen 100 that I have illustrated a slightly different form of apparatus for hardening the interior of comparatively short tubes, such as engine cylinders, etc. Referring to Fig. 5, 43 indicates the face plate of an ordinary lathe to which the tube 44 is secured by 105 means of the jaws 45. The outer end of the tube 44 may be supported in a suitable rest 46 and a head 47 is arranged on the interior of the tube and adapted to be moved longitudinally thereof by means of a rod or 110 tube 48 which is secured to the usual carriage 49, this carriage being moved back and forth on the bed of the lathe by the usual feed screw 50. A bracket 51 is secured to the head 47 by means of suitable bolts 52 and 115 insulated therefrom. A bell crank 53 is pivoted to the bracket 51 and also to an electrode holder 54. A link 55 also connects the holder 54 with the bracket 51, the arrangement of this link and the bell crank 53 being such that the holder 54 has a parallel motion. An electrode 56 is secured in the holder 54 in any suitable manner as by having the holder split along one side and clamped together by means of bolts or 125 screws passing through openings in the lugs 57. The bell crank 53 is provided with a counterweight 58 which balances the weight of the holder 54 and the electrode 56 and the rod 59 is pivotally connected with 130

the bell crank 53 and a second bell crank 60 which is pivotally supported on a bracket 61 arranged on the tube 48. The rod 59 is preferably formed in two sections which are connected together by an insulator 62. The bracket 61 also carries a feeding mechanism 63 for the electrode 56, this feeding mechanism being of any suitable construction and preferably of the type commonly used in arc lamps to feed the carbons. Electricity is passed from a source 64 through a rheostat 65, the feeding mechanism 63 and conductor 66 to the electrode holder 54 and from the latter through the electrode 56 and across the space between the end of the latter and the surface of the tube 44. The current passes to the rest 46 and through the conductor 67 to the source 64. A nozzle 68 is secured to the end wall of the head 47 and is in communication with the interior of the tube 48, the latter being supplied with a cooling agent from any suitable source. An ammeter 69 is arranged in the circuit for the purpose of indicating the current which is flowing therein.

The operation of this apparatus is similar to that shown in Fig. 1, the face plate 43 of the lathe being rotated and carrying with it the tube 44, and the head 47 being fed through the tube by means of the carriage 49 and the feed screw 50, and the arc traveling in a helical path relative to the tube 44. The current is maintained constant by the feeding mechanism 63 which, as will be readily understood, is adapted to vary the space between the end of the electrode 56 and the inner surface of the tube 44.

The two forms of apparatus just described are for hardening and tempering the interior surface of the tube. For the purpose of employing my improved method for hardening the exterior surface of a cylindrical body, the apparatus shown in Fig. 7 may be used. This apparatus consists preferably of an ordinary lathe; the head-stock being shown at 70 and the tail-stock at 71. Arranged in the lathe in the usual manner I have shown a reamer having the cutting head 72 and the cylindrical shank 73, the reamer being secured to the face plate 74 of the lathe by means of a dog or clamp 75. The carriage of the lathe, shown at 76 is moved longitudinally of the bed of the lathe by means of the usual feed screw 77. A bracket 78 is secured to the carriage 76 and supports a feeding mechanism 79 for the electrode 80, this feeding mechanism being preferably of the type commonly employed in arc lamps for feeding the carbons thereof. A nozzle 81 may be secured to the feeding mechanism 79 and supplied with a suitable cooling agent by means of a tube 82. A source of electricity 85 is provided, the current from this source passing through a rheostat 86 and a conductor 87 to the feed-

ing mechanism 79 and from the latter through the electrode 80 to the shank 73 of the reamer or other article being treated. The current passes through the article to the tail-stock of the lathe and from the latter it returns to the source through a conductor 88. An ammeter 89 may be provided to indicate the amount of current flowing through the circuit. In the operation of this apparatus the article is rotated in the usual manner and the electrode moved lengthwise of the article by means of the feed screw 77. In this way the arc is made to traverse the surface of the article in a helical path and as much of the surface as is desired may be treated. For the purpose of treating a cutting edge such as one of the edges of the reamer head 72 I have shown the carriage 76 and the bracket 78 and the mechanism carried thereby in a dotted position in Fig. 7. It will be understood that the apparatus may be identical with that just described with the exception that in treating the cutting edge the article is not rotated. In this case only the feed screw 77 will be operated so that the electrode 80 will travel lengthwise of the article over the cutting edges thereof. When an article, such as a reamer having spirally arranged cutting edges, is to be treated it will be observed that the same apparatus may be used except that in this case the article will be rotated sufficiently in relation to the longitudinal feed to accurately follow the cutting edge. In Fig. 8 I have shown the relation of the electrode 80 to the cutting edges of the reamer head 72 in hardening and tempering the same.

In Fig. 10 I have illustrated an apparatus for hardening a flat surface. In this apparatus I employ a suitable bed or support 90 in which is arranged the article 91 to be treated. The bed 90 is illustrated as a trough which is adapted to contain a cooling agent, such as water, the water preferably rising to a point just below the top surface 110 of the article to be treated so that the larger portion of the article will be submerged. The bed is provided with ways 92 on the opposite sides thereof and a carriage 93 is arranged to be moved back and forth along these ways. A head 94 is slidably arranged on the carriage 93 and is moved back and forth thereon transversely of the ways 92 by means of a suitable screw 95 which may be operated by a crank 96. The carriage 93 is moved along the ways 92 by means of feed screws 97 and 98 which are preferably operated from a common shaft 99 by means of the bevel gears 100. The head 94 carries an electrode feeding mechanism 101 for an electrode 102 which has its lower end arranged slightly above the article 91 so that an arc will be formed between the end of the electrode and the article when a current is passed through the electrode. A bracket 130

103 is carried on the head 94 and supports the conductor 104 and also the pipe 105 for the cooling agent, the latter terminating in a nozzle 106 adjacent the end of the electrode 102. A source of electricity 107 is provided and the current from this source passes through a rheostat 108 and the conductor 104 to the feeding mechanism 101 and from the latter through the electrode 102 to the article 91. From the article 91 the current returns to the source by means of a conductor 109. An ammeter 110 may be provided in the circuit for the purpose of indicating the amount of current flowing.

15 In Fig. 9 I have shown a modified form of electrode in which two carbons 111 and 112 are employed, the arc being formed across the adjoining ends of these carbons. For the purpose of directing the arc against 20 the surface 113 to be treated either a blast of air or a magnet 114 may be employed, these being common devices for deflecting an arc.

Having thus described the invention what 25 is claimed as new is:

1. The method of hardening a cylindrical surface of a piece of metal which consists in applying an electric arc to the surface and relatively rotating the arc and surface 30 and also imparting a relative axial movement until the entire surface to be treated has been traversed by the arc.

2. The method of surface hardening a cylindrical surface of a piece of metal which consists in subjecting the surface to an electric arc, and imparting a rotary movement to the surface and an axial movement to the arc whereby the entire cylindrical surface may be treated. 35

3. The method of surface hardening a 40 piece of metal which consists in applying an electric arc thereto, causing the metal and arc to travel relatively, and rapidly absorbing the heat from the path of the arc in 45 the rear thereof.

4. The method of surface hardening a piece of metal which consists in applying an electric arc thereto, causing the metal and arc to travel relatively, and rapidly cooling 50 the surface in the path of the arc immediately after the passage of the arc.

5. The method of surface hardening a piece of metal which consists in applying an electric arc thereto, causing the metal and arc to travel relatively, and rapidly cooling 55 the surface in the path of the arc and immediately in the rear of the arc by directing thereon a stream of cold fluid.

In testimony whereof I affix my signature in presence of two witnesses.

JOHN PATTEN.
